REFLECTOR TYPE SIGNAL FOR SWITCH STANDS

Godfrey Gort, Chicago, Ill., assignor to Western Railroad Supply Company, Chicago, Ill., a corporation of Delaware

Application November 27, 1935, Serial No. 51,867

5 Claims. (Cl. 88—78)

This invention relates to reflector type switch stand signals, particularly adapted to be mounted on conventional rotatable switch stands and to be rotated with said stands to display one of a plurality of colored signals for the guidance of the engineer of an approaching locomotive.

Structures of the character described are designed to be used in place of prior art oil and electric lamps provided with lenses of different colors, heretofore adjustably mounted on switch stands and adapted to be rotated therewith to display one of a plurality of said lenses.

The main object of this invention is to provide a reflector type signal, simple and durable in construction, easily assembled, in which the reflector elements are mounted in a housing by efficient and economical means, and are protected against breakage.

Other advantages will be disclosed in the following specification.

In the drawings:—

Fig. 1 is a side elevation of a reflector type signal for switch stands embodying my invention.

Fig. 2 is a vertical sectional view of the same.

Fig. 3 is a detailed view of a part of the means for mounting a reflector unit in the signal housing.

Fig. 4 is a horizontal sectional view taken on the line 4—4 of Fig. 1 looking downwardly as indicated by the arrows.

Fig. 5 is a bottom plan view of my invention.

In that embodiment of the invention shown in the drawings, the reflector type signal comprises a housing having a plurality of side walls 10, preferably integral with each other and with end members 11 which form the bottom of the housing. The top 12 closes the top of the housing and extends beyond the side walls 10 as shown in Fig. 2. The means for assembling these parts will be described hereinafter. The outer edges of the top 12 are flanged as indicated at 13. A grille, preferably integrally formed of metal, is secured to the flanged top by rivets 14, and extends downwardly to the plane of the bottom 11 of the housing, the metal being bent to provide walls 15 equal in number to the side walls 10 of the housing. The grille walls 15 are wider than the housing walls 10 and are spaced from said walls. That part of each grille wall 15 which is opposite the face of a housing wall 10 is so constructed that the said wall 10 is visible through the grille work, and the part 16 at each side of said wall 15 is preferably imperforate, for a purpose hereinafter explained. The side edges of the grille are connected together at 17. Reinforcing and spacing

brackets 18 are located between the top flange 13 and faces of the housing walls 10 and are secured to said flange 13 by the rivets 14 which also connect the grille 15—16 to said flange of the top 12.

Each of the walls 10 is provided with an opening 19, preferably circular, closed by a reflector device 20 of the "Corning" type. Such reflector devices are available on the market and comprise a light diffusing lens 21 mounted in the flanged ring 22 of an internally reflector-surfaced back plate 23. The reflector device 20 is mounted on the inner surface of the wall 10, and retained at the top by the removable L-clip 24 engaging the wall 10 and the shoulder formed by the ring 15 flange 22 and back plate 23, held in place by the bolt 25 and wing nut 26 (Fig. 2). At the bottom, the reflector device 20 is retained by a spring metal bracket 27 secured to the housing wall 10 by rivets 28. The reflector part 22 has an indentation 22' engaged by a projection on the bracket 27 (Fig. 3) which prevents rotation of the reflector device 20.

The bottom 11 of the housing is reinforced by a ring 29 having screw threaded bosses 30 which register with holes in the bottom 11, for the reception of screw-threaded bolts 31 fixedly held in said bosses 30. A coupling for mounting the signal on a conventional switch stand comprises a hollow stem 32, set screw 33, top plate 34 and radial flange 35. The flange 35 is provided with curved slots 36 through which the projecting ends of the bolts 31 extend. The curved slots 36 permit the coupling flange 35 to be secured to the housing in adjusted position by means of the theft-proof nuts 37. The hollow stem 32 may be made to fit any switch stand on which the signal is to be mounted. A rod 38 having a screw threaded end 39 is screwed into the center of the coupling plate 34 to extend upwardly above the upper edges of the housing walls 10. Near the upper end of the rod 38 is fixed a nut 40. The top 12 rests on the nut 40 and upper edges of the housing walls 10, and is held in place by a theft-proof nut 41 on the upper end of the rod 38.

The reflector unit 20 is readily slipped into position between the spring bracket 27 and wall 10, and then the L-clip 24 and wing nut 26 are placed on the bolt 25 to retain the parts in position.

From the foregoing description it will be understood that in the preferred embodiment of my invention the top 12 and grille 15—16 are connected together and form a unitary structure, that the housing walls 10 carrying re-

5 reflector units 20, and bottom 11 with ring 29 and bolts 31 mounted therein form another unit, and that these units and the coupling 32-35 may be easily assembled by fastening the nuts 37 on bolts 31 to adjustably connect the housing and coupling, and by fastening the nut 41 on the rod 38 to rigidly connect the top with its protecting grille in position on the housing.

10 An advantage of the construction described is the ease of assembling the parts and the fact that the interior of the signal is readily accessible by the removal of the single nut 41 which permits the top 12 and connected grille to be lifted from the top of the housing.

15 It will be understood that the lens 21 of one reflector unit 20 will usually be of a color indicating that the track is clear, and the lens or lenses at right angles thereto (assuming the housing is a four sided one) will be of a different color to indicate danger. The imperforate parts 16 of the grille walls 15 function as ray confiners so that rays which may be reflected from one reflector unit are not visible to one observing another reflector unit. The grille walls 20 protect the reflector units against breakage without interfering with the efficiency of the reflector units for their intended purposes.

Changes may be made in details of construction without departing from the scope of my invention and I do not intend to be limited to the exact form shown and described, except as set forth in the appended claims.

I claim:—

1. A reflector type signal comprising a plurality of side walls forming an open-top housing, each side wall having a reflector mounted therein, a top wall removably seated on the upper edge of said housing and extending beyond the side walls thereof, a grille connected to the edges of the top wall and suspended therefrom in spaced relation to said side walls and reflectors, whereby said top wall and grille may be removed as a unit for gaining access to said reflectors.

45 2. A reflector type signal comprising a plurality of side walls forming an open-top housing, each side wall having a reflector mounted therein, a top wall removably seated on the upper edge of said housing and extending beyond

the side walls thereof, a grille connected to the edges of the top wall and suspended therefrom in spaced relation to said side walls and reflectors, said grille comprising an integral piece of metal having grille-like portions located opposite said reflectors and imperforate sections located at each corner between said grille-like portions.

3. A reflector type signal comprising a plurality of side walls forming an open-top housing, each side wall having a reflector mounted therein, a top wall removably seated on the upper edge of said housing and extending beyond the side walls thereof, said top wall having wall portions connected together at right angles depending from the edges of the top wall to enclose said housing in laterally spaced relation thereto, a section of each of said wall portions opposite a reflector being perforated to form a protecting grille therefor.

10 4. A reflector type signal comprising a plurality of side walls forming an open-top housing, each side wall having a reflector mounted therein, a top wall removably seated on the upper edge of said housing and extending beyond the side walls thereof, said top wall having wall portions connected together at right angles depending from the edges of the top wall to enclose said housing in laterally spaced relation thereto, a section of each of said wall portions opposite a reflector being perforated to form a protecting grille therefor, said protecting grille having imperforate corner sections between said perforated sections.

15 5. A reflector type signal comprising a plurality of side walls forming an open-top housing, each side wall having a reflector mounted therein, a top wall removably seated on the upper edge of said housing and extending beyond the side walls thereof, a grille connected to the edges of the top wall and suspended therefrom in spaced relation to said side walls and reflectors, said housing having a bottom wall, a ring resting on said bottom wall within the housing, a coupling having a flange supporting the housing, said flange having spaced slots therein, bolts passing through said ring, bottom wall and slots for mounting the housing on said coupling.

GODFREY GORT.
